UNITED STATES PATENT OFFICE.

THOMAS P. FITZGERALD, OF WASHINGTON, DISTRICT OF COLUMBIA, ASSIGNOR OF TWO-THIRDS TO WILLIAM E. DE WITT AND ONE-THIRD TO DANIEL J. RADY, BOTH OF WASHINGTON, DISTRICT OF COLUMBIA.

WATER AND GAS BOX FOR SERVICE-PIPES.

No. 911,485.

Specification of Letters Patent.

Patented Feb. 2, 1909.

Application filed September 5, 1906. Serial No. 333,348.

To all whom it may concern:

Be it known that I, THOMAS P. FITZGERALD, a citizen of the United States, residing at Washington, in the District of Columbia, have invented certain new and useful Improvements in Water and Gas Boxes for Service-Pipes; and I do declare the following to be a full, clear, and exact description of the invention, such as will enable others skilled in the art to which it appertains to make and use the same, reference being had to the accompanying drawings, and to the letters of reference marked thereon, which form a part of this specification.

This invention relates to new and useful improvements in water and gas boxes for service pipes, and the object of the invention is to produce a simple and efficient device of this nature which is to be so arranged that the covers of the boxes may be securely held in place and so arranged that they will indicate when water is turned on to a building from a main, or closed.

The invention comprises various details of construction and combinations and arrangements of parts which will be herein-after fully described and then specifically defined in the appended claim.

I illustrate my invention in the accompanying drawings, in which:

Figure 1 is a top plan view showing the cover indicating the water turned on to a building from a service main. Fig. 2 is a similar view showing the cover indicating the water turned off from the building. Fig. 3 is a vertical sectional view on line 3—3 of Fig. 4, and Fig. 4 is a sectional view on line 4—4 of Fig. 3.

Reference now being had to the details of the drawings by letter, A designates a metallic boxing having threads A' about the lower portion thereof and adapted to be connected to a service main, and to surround a valve connection located at the lower end of the boxes. Projecting from the inner surface of the upper portion of the box is an integral finger B which has a threaded aperture to receive the retaining screw D, the head of which rests upon the upper surface of a countersunk portion of the cover, the shank of said screw passing through an aperture in said countersunk part of the cover.

F designates a cover having a flange F'

and a cylindrical shell portion F² which is adapted to telescope within the upper end of the box. Lugs K project from the circumference of the cylindrical shell portion of the cover and are adapted to engage the recesses N which are formed longitudinally in the inner walls of the boxing, said recesses being clearly shown in the sectional view of the drawings. Said lugs K are of such size as to conveniently engage the recesses N and prevent the cover from being rotated when adjusted in place. In order to reinforce the upper portion of the box adjacent to the inner end of the cylindrical portion of the cover and the recessed part of the boxing, a rib or beading O is formed about the outer circumference of the boxing and cast integral therewith.

Referring to the top plan view, Fig. 1, will be seen an arrow R indicating the direction in which communication is had between the service and the main and indicating that the water is turned on and, in Fig. 2, is shown an arrow pointed at right angles to the position shown in Fig. 1 and indicating that communication is turned off from the branch leading from the street main.

Upon the cover preferably appears suitable wording indicating that the top to the box has been adjusted by the proper officials, and being so arranged that any tampering with the cover other than by the proper officials may be readily detected.

From the foregoing, it will be noted that by the provision of the apparatus shown and described, a simple and efficient means is afforded whereby the covers for water and gas boxes for service pipes may be securely held within the boxes, even though the retaining screw may be detached therefrom, making a secure fastening for the cover and so arranged that the valve, access to which is had through the boxing by means of a suitable key, may be turned on or off and so indicated by the manner of placing the cover upon the box, thus affording means whereby should the cover be changed by any unauthorized person seeking to tamper with the water main or valve connections therewith, it can be readily detected.

What I claim is:

A water and gas box apparatus for service mains comprising a metallic body portion provided with longitudinally formed slots in

the end wall thereof spaced apart, a beading about the outer circumference of said body portion adjacent to the inner end of said slots, an apertured lug projecting from the 5 inner surface of said body portion opposite the lower portion of said bead, a closure adapted to telescope within said body portion and provided with lugs upon its circumference for engagement with said slots, said 10 lugs designed to rest upon the inner end walls of said slots, the closure having a flange

designed to rest upon the end of said body portion, a headed screw passing through the end of the closure and engaging a threaded aperture in said lug, as set forth. 15

In testimony whereof I hereunto affix my signature in presence of two witnesses.

THOMAS P. X FITZGERALD.
mark.
